DESIGN FOR A SUN SHIELD

Rose Ehrlich, New York, N. Y., assignor to Lapin-Kurley Kew, Inc., New York, N. Y., a corporation of New York

Application March 16, 1938, Serial No. 75,870

Term of patent 14 years

To all whom it may concern:

Be it known that I, Rose Ehrlich, a citizen of the United States, residing at New York, County and State of New York, have invented a new, original, and ornamental Design for a Sun Shield, of which the following is a specification, reference being had to the accompanying drawing, forming part thereof.

Fig. 1 is a perspective view showing the new design of a sun shield.

Fig. 2 is a front view of the same.

Figs. 3 and 4 are sectional views as on lines 3—3 and 4—4 of Fig. 1.

The distinctive features of the design are the characteristic molded appearance of the parts, conspicuous by the smoothly rounded edges, the variations in thickness of material particularly evident at the thickened bridge and nose pads and the temples hollowed at the inside and merg-

ing rearwardly into the thicker inwardly convergent head embracing bows and the inwardly projecting flanges along the upper and lower edges of the temples; also the straight substantially continuous upper edge and the downwardly and laterally curved lower edges of the front eye shielding portion and the temples joined by concealed hinges in abutting engagement with the front portion on downwardly and outwardly flaring hinge axes (Fig. 2) and tapering continuously in unbroken curved lines from the outwardly flaring end edges of the front part to the bow portions at the rear.

I claim:

The ornamental design for a sun shield, substantially as shown and described.

ROSE EHRLICH.
